SCATTERING UNLOADING MACHINE

Erwin J. Erp, Des Moines, Iowa, assignor to Brady
Manufacturing Corporation, Des Moines, Iowa, a cor-
poration of Ohio

Filed Dec. 31, 1963, Ser. No. 77,991

Term of patent 14 years

(Cl. D35—2)

FIG-1

FIG-2

FIG-3

FIG-4

FIG-5

FIG. 1 is a rear perspective view of a scattering unloading machine showing my new design;

FIG. 2 is a rear elevation of the machine shown in FIG. 1;

FIG. 3 is a front perspective view of the machine looking at a side opposite to that of FIG. 1;

FIG. 4 is a front elevational view; and

FIG. 5 is a side elevational view.

I claim:

The ornamental design for a scattering unloading machine, as shown.
